UNITED STATES PATENT OFFICE

ERNST VOGEL, OF STOCKERAU, NEAR VIENNA, AUSTRIA

MULTISTAGE HIGH-PRESSURE CENTRIFUGAL PUMP

Application filed February 8, 1927, Serial No. 166,768, and in Austria February 9, 1926.

Multi - stage high - pressure centrifugal pumps, especially boiler feed pumps for high-pressure boilers, up to the present are built in such a manner, that the shaft carrying the 3 rotor-wheels is supported on both sides of the pump, thus requiring on the one side a low-pressure or suction-stuffing-box and on the other a high-pressure-stuffing-box.

According to the present invention the 10 high-pressure-stuffing-box is eliminated, because it is very difficult to keep it constantly tight at the high rotary speed of the shaft in the warm, or hot water, and, therefore, retightening very frequently becomes necessary.

This, according to the invention, is obtained by providing bearings for the pump-shaft at the suction-side of the pump only, hence making the other end of the shaft self- 20 supporting, and by neutralizing, wholly or partly, the axial pressure (high-pressure) on the free cross-section-area of the non-supported shaft-end by means of a tightening-device, which permits, at all or at only some 25 or at only a single one of the rotor-wheels, the hydraulic pressure active at their periphery to act on the wheel-face facing the suction-side as an axial-pressure opposite in direction to the axial-pressure mentioned above.

30 In the example shown in the drawing as a longitudinal view partly in section, a pump is driven by an electric motor or a steam-turbine.

Therefore a strong shaft 1 is used which is 35 supported, at the suction-side of the pump, at the suction-canal 2, in two bearings, f. i. ball-bearings 3 and 4. These bearings are arranged so far from each other that the pump-shaft is self-supporting without danger of 40 bending or vibration. The shaft carries a number of rotor-wheels 5 which cooperate with the corresponding fixed casings 6. These casings 6 are surrounded by outer casings 7 to which the casing-like lids 8 and 9 45 are connected for supporting the pump. The lid 8 carries the suction-stuffing-box 11 accessible through opening 10 and, by means of a suitably adjoined hollow lengthening-piece 12, the bearings 3 and 4 mentioned above.

50 The lid 9 forms the high-pressure chamber 13

to which, at 14, the pressure-conduit is joined. In this chamber the free end of the shaft 1 protrudes and the total cross-area of this end is acted upon by the hydraulic high-pressure which exerts on the shaft 1 an axial-thrust toward the suction-side. In order to neutralize this axial thrust wholly or partly on both side-faces of all or part of the wheels 5, annular tightening rings 15, 16, are provided, these rings differing in diameter so that the hydraulic pressure, active at the circumference of the wheels and transmitted to both side-faces of the wheels, meets a larger annular pressure-area (ring-breadth 17) at the side-face of the wheels facing the suction-side of the pump than at the side-face (ring-breadth 18) facing the pressure-side of the pump, so that the difference of the two pressures at the stage concerned exerts an axial-thrust opposite in direction to the axial high-pressure mentioned above. If the sum of the axial thrusts acting on the individual stages is made equal to the axial high-pressure acting on the cross-area of the shaft and corresponding to the end-pressure of the pump, 75 the axial thrusts will balance each other. The shaft 1, then, is relieved and has no need of a special device for taking-up an axial thrust. Inside the tightening-rings 15, 16, due to the borings 19 provided in the wheels, 80 the same pressure prevails on both sides.

The ball-bearings 3 and 4 are so-called radial bearings which are movable in an axial direction and will take up the radial strains on the shaft 1. Any further axial 85 thrust, will be taken up by a third bearing 20 which is not movable in an axial direction and is not subject to radial strains. This bearing, thus, fixes the shaft 1 in an axial direction, f. i. by means of the collar 21 and the 90 ring 22, and relieves the two radial bearings 3 and 4 from an axial thrust. The taking-up of the remaining axial thrust of the shaft 1 is effected more advantageously by a bearing not movable in an axial direction than by a 95 so-called axial-bearing, because, with the latter, on account of the centrifugal force acting on the balls a wedging-in of the balls will occur in the narrowing space between the grooves of the two bearing-rings. 100

What I claim is:

1. A multi-stage high-pressure centrifugal pump comprising a plurality of impellers on a common shaft, said shaft being supported only at the suction-side of the pump, the cross-section of the non-supported end of said shaft being acted upon by an axial high-pressure, means provided at a plurality of said impellers for putting in action the pressure generated by said impellers on the face of said impellers facing the suction-side of the pump as a constant axial pressure counteracting the axial high pressure, whereby a plurality of such pressures counteract the axial high-pressure and balance it.
- 10 2. Multi-stage high-pressure centrifugal pump according to claim 1, wherein the non-supported end of said shaft enters the discharge chamber of the pump.
- 15 3. Multi-stage high-pressure centrifugal pump according to claim 1, said means consisting of tightening-rings of different diameters, the tightening-ring of greater diameter being arranged on the face of the impellers facing the pump discharge.
- 20 25

In witness whereof I have hereunto signed my name.

ERNST VOGEL.
